JOSEPH CONNER, JR., OF CHICAGO, ILLINOIS.

Letters Patent No. 78,263, dated May 26, 1868.

IMPROVED STAIR-CARPET FASTENER AND PROTECTOR.

The Schedule referred to in these Letters Patent and making part of the same.

TO ALL WHOM IT MAY CONCERN:

Be it known that I, JOSEPH CONNER, Jr., of Chicago, in the county of Cook, and State of Illinois, have invented a new and improved Carpet-Fastener and Protector; and I do hereby declare that the following is a full, clear, and exact description thereof, reference being had to the accompanying drawings, making part of this specification, in which—

Figure 1 is a perspective view of two steps, showing the improved fastener applied to one of them.

Figure 2 is a top view of the fastener.

Figure 3 is an end view of the fastener in two positions.

Similar letters of reference indicate corresponding parts in the several figures.

The object of this invention is to protect stair-carpets from being readily soiled and worn out by stepping upon them, and at the same time to afford a simple and efficient means for fastening down such carpets upon the stairs. The invention consists in a device which, when it is applied to a carpet upon a stair-step, will serve as a means for securing such carpet down firmly in place, and also afford a cover which will protect the carpet from being stepped upon by persons ascending and descending the stairs, as will be hereinafter described.

To enable others skilled in the art to understand my invention, I will describe its construction and operation.

In the accompanying drawings, the improved fastener and protector is represented as being constructed of a thin plate, B, of metal or other suitable substance, which may be made with fancy open work, b, which will expose to view the carpet upon which it rests, and present a neat and handsome appearance when upon a step, A, as shown in figs. 1 and 2. This covering-plate B may be made solid, but I prefer to make it open, as shown in the drawings, for the purpose above stated, and it may be made whole or in part of hardened India rubber, or other substance which will answer the purpose.

The front and rear edges of the covering-plate B are parallel with each other, and the front edge is made with a depressed lip, a, which is adapted to fit over the front edge of the step, and protect the stair-carpet at this point; also to prevent the cover from being accidentally thrown up by the feet of a person ascending the stairs. Said edge is also elevated above the main surface of the plate, in order to prevent liability of slipping.

The extremities of the back part of the cover B are extended, so as to form means by which the cover can be attached to ears e, which are fastened upon the step outside of the carpet, as shown in figs. 1, 2, and 3. These extensions C C are made with hooked extremities, and are adapted to slip into the circular opening in the ears e e when the cover B is in the position shown in red in fig. 3, and when this cover is swung down in place upon the step, the ears will keep its rear edge firmly in place, and thus hold the carpet closely into the angle formed by the step and its riser. It will be seen that the cover can be thrown up at any time, when it is desired to remove it, or to sweep the carpet beneath it.

The device thus described serves two purposes, namely, it serves as a stair-rod for holding the carpet in place upon the stairs, and it also serves as a covering for that portion of the carpet which is upon a step, so that while the carpet can be exposed to view, it cannot be stepped upon by persons ascending or descending a staircase.

I do not confine myself to the combined stair-rod and carpet-protector, constructed precisely as I have shown and described, as the device may be made of various forms and designs, and fastened to a step in different ways. I prefer, however, to have the fastenings made so that the covers can be readily attached and detached, for convenience of removing it, when it is desired to sweep beneath it. The bearings or ears e, which I have shown, are made so that while the flat extremities C can be readily introduced into these ears when the cover is in an upright position, this cover cannot be removed unless it is first adjusted in such position as above shown and described.

Having described my invention, what I claim as new, and desire to secure by Letters Patent, is—

1. A device, B, having axial extensions e e, the same constituting a combined stair-rod and protector, or stair-carpet fastener and protector, substantially as and for the purpose described.
2. The combined stair-rod and protector B e, in combination with the ears or holders e e, substantially as described.
3. The depressed lip a, on the front edge of the protecting-cover B of the combined stair-rod and protector, as described.

JOSEPH CONNER, Jr.
